ELECTRIC FARM GATE

Charles E. Young, New London, Iowa

Application December 20, 1946, Serial No. 717,483

2 Claims. (Cl. 39—7)

2

This invention relates to an electric farm gate, which is operated by an approaching vehicle, so that the gate may be opened or closed as desired.

An object of this invention is to provide a gate that is simple in construction, and operation, efficient and durable in use, and can be inexpensively manufactured for the purpose designed.

With the above and other objects in view, the invention consists in the novel details of construction, arrangement and combination of parts more fully hereinafter described, claimed and illustrated in the accompanying drawings in which:

Figure 1 is a side elevational view, partly in section, of a gate embodying the invention;

Figure 2 is a top plan view thereof;

Figure 3 is an end view thereof;

Figure 4 is a sectional view on the line 4—4 of Figure 3;

Figure 5 is a detailed sectional view of the adjusting plate and actuating arm and

Figure 6 is a modified form of adjusting plate.

Referring more in detail to the drawings, the reference numeral 10 designates a gate which by means of pivot pins 11 is swingably mounted in the eyes 12 which are mounted in the cross bars 13 and 14 respectively. The bars 13 and 14 are secured at their ends in spaced horizontal relation to each other to the posts 15, which are embedded in the ground as shown in Figure 3. Mounted between the posts 15, is a housing 16, having a rear wall 17, which is detachably secured to the housing by fasteners 18, and the housing rests on the base 19, on which is mounted the metal frame 20. An electric motor 21 is mounted in the frame and the drive shaft 22 thereof carries a bevelled gear 23 which engages a bevelled gear 24, of larger diameter, which is fixed to the vertical shaft 25 journalled at its end in the frame 20. A gear 26 fixed to the shaft 25 upwardly of the gear 24 engages a gear 27 of larger diameter which is fixed to the vertical shaft 28 which is parallel to the shaft 25, and is also journalled in the frame 20. The frame 20 is secured to the base by fasteners 29, and apertured ears 30 receive the fasteners 18.

The shaft 28 extends outwardly of the housing 17 to have a perforated disc 31 secured to the upper end thereof. An operating rod 32 is provided with a hooked end that is adapted to be adjustably inserted in the perforated disc 31 to determine the amount of throw of the gate 10. The opposite end of the rod 32 is flattened as at 33 and provided with an elongated slot 34 which is adapted to engage the pin 35 fixed to the circu-

lar plate 36, which by means of a flange 37 cut out from the plate, is secured to the gate 10 by any conventional means. A sleeve 38 secured to the gate by a flange 39 loosely mounts the substantially U-shaped lever 40 having an arm 41 adapted to be engaged by the rod 32 and an arm 42 pivoted at 43 to the rod 44, which extends longitudinally of the gate and is slidably mounted in the gate. The rod 44 extends beyond the gate to be fastened to the spring latch 45, which is secured to the gate 10 by fasteners 46.

An eye 47 in one of the posts 15 is connected to one end of a coil spring 48 while an eye 49 in the gate 10 is connected to the other end of the spring.

When the gate is mounted, the posts 15 and housing 16 are mounted inwardly of the post 50 of the fence 51, which is in vertical alinement with the post 50, and a keeper 53, secured to the post 52 by fasteners 54 engages the latch 45 to retain the gate closed.

In Figure 6, a bar or arm 54 is shown, which is provided with a square opening 55 for connection to the shaft 28 and spaced openings 56 for connection to the rod 32. Thus the arm or bar 54 can be substituted for the plate 36 if desired.

In operation, the motor 21 is controlled at a suitable location by any well known means for the energizing thereof. When the motor has been energized, it causes the rotation of the gears and subsequent rotation of the disc 31 which causes the rod 32 to swing the gate open by means of the engagement therewith of the stud 35 in the plate 36. As the rod 32 moves, it strikes the arm 41 of the lever 40, causing the lever to draw the rod 44 rearwardly and disengage the latch 45 from the keeper 53. Continued operation of the motor will close and lock the gate upon release of the arm 41 from engagement with the rod 32.

There has thus been provided a gate which is adapted to be opened and closed by a motor which is energized from a location remote from the gate. It is believed that from the foregoing description, the construction and operation of the invention will be apparent to those skilled in the art, and it is to be understood that changes in the minor details of construction, arrangement and combination of parts may be resorted to, provided they fall within the spirit of the invention and the scope of the appended claims.

Having thus described the invention, what is claimed as new and desired to be secured by Letters Patent is:

1. A support and operating mechanism for a

gate, comprising vertical supports, a gate, means 5 swingingly mounting the gate from the supports, a housing mounted between said supports, vertical shafts journaled in said housing, gear connections between said shafts, a motor in said housing, gear connections between said motor and one of said shafts whereby both shafts are rotated simultaneously, an apertured member on the upper end of one of said shafts, a circular plate fixed to said gate, an eccentrically mounted 10 pin on said plate, and an operating rod having a hooked end engaged with a selected aperture in said apertured member, said operating rod provided at its other end with an elongated slot through which said pin passes whereby movement of said apertured member will open or 15 close the gate, and the apertured member and slotted end of said operating rod constituting means through the medium of which the effective length of the operating rod may be varied. 20

2. The invention as claimed in claim 1, wherein a latch is provided for said gate, a shaft journaled on the gate and provided with upper and lower arms, and a rod connecting the latch with

one of said arms, the other arm being arranged in contact with that end of the operating rod having the slotted end whereby said rod will retract the latch while being moved to open the gate.

CHARLES E. YOUNG.
